UNITED STATES PATENT OFFICE.

RICHARD FRED. PREUSSER, OF LAMBERTVILLE, NEW JERSEY.

SAD-IRON.

SPECIFICATION forming part of Letters Patent No. 289,709, dated December 4, 1883.

Application filed June 5, 1883. (Model.)

To all whom it may concern:

Be it known that I, RICHARD F. PREUSSER, a citizen of the United States, residing at Lambertville, in the county of Hunterdon and State 5 of New Jersey, have invented certain new and useful Improvements in Sad-Irons, of which the following is a specification, reference being had therein to the accompanying drawings.

This invention relates to certain improvements in sad-irons or smoothing-irons; and it has for its objects to provide an iron of such construction as to receive a handle attachment, which can be so affixed as to permit a current of cold air to pass between it and the iron when 10 in place, and thus prevent the heating of the handle, and by means of which any number of irons may be employed—one at a time—with but one handle attachment.

The above-mentioned objects I attain by the 15 means illustrated in the accompanying drawings, in which—

Figure 1 represents an isometrical view of my improved iron; and Fig. 2, a longitudinal vertical sectional view thereof.

25 The letter A indicates the iron, which is of the usual form, with the exception of the handle. The said iron at its top is provided with raised projections B, which form seats for the plate C, which is secured by means of screws 30 D pressing into threaded apertures in said projections. The upper surface of the plate C is provided with two parallel longitudinal ribs, D', between which is adapted to set a detachable plate, E, which has recesses F at each 35 side, which fit over the ribs. The said plate C is provided with a slot, G, near its center, through which is adapted to pass the hooked end of a lever, H, which is fulcrumed in bear-

ings K on the plate E, the hooked portion of said lever extending through a slot in said plate. The lever is provided with a knob or button, L, by which it may be operated, and is held in and returned to a normal position by means of a spring, M. The plate E at each end is provided with socketed projections N, 45 with which the ends of the handle P set, and are secured by means of screws. The handle is made of bent wood or other suitable material.

The operation of my invention will be readily 50 understood from the above description, and is as follows: A set of irons of any desired number may be employed. These are heated, and, as required for use, are attached to and detached from the handle by means of the hooked 55 lever. The space between the iron and the plate secured to the same, by leaving a body of air between the two, will prevent inconvenience to the hand from transmitted or radiated heat.

Having thus described my invention, what 60 I claim, and desire to secure by Letters Patent, is—

The combination, in a sad-iron, A, having 65 projections B on top, of the plate C, secured thereto by means of the screws D, and provided with ribs D', the detachable plate E, and hooked lever H, and its spring M and button L, and the handle P, all constructed and adapted to operate substantially as specified.

In testimony whereof I affix my signature in presence of two witnesses.

RICHARD FRED. PREUSSER.
